Inventor

S. M. Sherman
by J. W. Beadle
Attn

S. M. SHERMAN, OF FORT DODGE, IOWA.

Letters Patent No. 84,913, dated December 15, 1868.

IMPROVED WINDOW-SHUTTER.

The Schedule referred to in these Letters Patent and making part of the same.

To all whom it may concern:

Be it known that I, S. M. SHERMAN, of Fort Dodge, in the county of Webster, and State of Iowa, have invented new and useful Improvements in Window-Blinds; and I do hereby declare that the following is a full and exact description of the same, reference being had to the accompanying drawings, and to the letters of reference marked thereon.

This invention relates to window-blinds, and consists mainly in the manner of hanging the slats, and in certain novel devices for operating them, the details of which will be fully described hereinafter.

In the drawings—

Figure 1 is a front elevation of a window with my improved attachment;

Figure 2, a perspective view, showing one method of attaching the blind-rod to the slats;

Figure 3 is a perspective view, showing my invention as applied to inside shutters;

Figures 4 and 5 are sectional views through $x-x$, fig. 1; and

Figures 6 and 7 are plan views of the end-clamps $a a'$.

To enable those skilled in the art to which my invention appertains, to make and use the same, I will now proceed to describe fully the details of construction and manner of operation.

A represents the frame of a blind, constructed in the ordinary manner.

Instead of making holes, however, for the journals of the slats to rest in, as in the ordinary way, I insert journals into the frame, upon the outer edge of the blind. These journals extend entirely through the frame.

The slats A', I make much thinner than those ordinarily in use, and protect the ends with the sheet-metal clamps $a a'$, which form bearing-surfaces for them to turn upon, and by which means also they are prevented from splitting.

The clamps $a a'$ are somewhat differently constructed from each other. The former, a , being intended only to form a bearing-surface for the journal, is more simple than the latter, a' , which not only forms the bearing-surface, but is also used as a lever to move the slats, when desired. They each, however, are constructed of a single piece of metal, which is cut in the proper shape, and afterwards bent.

The appearance of the slats, when complete and in position, is clearly shown in fig. 1.

B represents the blind-rod, which, in my improved arrangement, I place by the side of the slats, as shown in fig. 1, instead of behind them.

To the side of this rod are attached, in any suitable manner, the lever-ends of the clamps $a a'$. By moving the rod in the ordinary way, the blinds are adjusted as desired.

It will be observed that when the slats are open, the rod does not project beyond them, by which arrangement all danger of striking the window-sash is avoided.

When the slats are closed, the rod rests in a recess in the frame, so that in both positions it projects much less from the blind than when arranged in the ordinary manner.

c represents a rod or bar, attached to the upper end of the blind-rod, the lower end of which is pivoted to the crank or cam d, as shown.

This cam is securely attached to the frame A, in such manner as to swing freely, and is constructed with a square socket, as shown.

By inserting a suitable key into this socket, the cam may be turned, and the blind operated, as desired.

By making a suitable opening in the window-sash, in line with this socket, the slats may be operated from the inside of the room with perfect ease.

It is only necessary that the key extend through the sash, and be provided with a suitable knob or handle, for the purpose of operating it.

The outer end of the key may be made of a square, tapering form, by which means it is readily inserted into the socket.

The blinds also may be opened, when desired, without drawing out the key, as the latter readily becomes disengaged.

The key for operating the upper set of slats is arranged in the same way. It passes through the upper sash, over the meeting-rail, in which position it also serves as a secure window-fastening.

Some of the advantages of the construction and arrangement described are as follows:

The journal or bearing being upon the inside of the slats, their weight presses outward and downward, by which means they naturally remain closed, and cannot be opened by a gust of wind, as is frequently done with the ordinary slats. The blind-rod is out of the way, and all danger of striking the sash avoided. The blinds are more durable, although made of a less amount of material. They are easily operated without raising the window.

My devices for operating the slats may be easily applied to the ordinary blind, as shown in fig. 1.

e represents the cam.

e¹, the connecting-link.

e², a bell-crank.

e³, the bar attached to the blind-rod.

By moving the cam, the slats are operated as before.

In fig. 2, another method of operating the ordinary slats is shown.

The rod h, instead of being attached by staples in the middle, is placed at the side, the attachment being made by a sheet-metal clamp, h', as shown.

This is much more substantial than the ordinary arrangement, and puts the rod entirely out of the way.

A still further modification of the described arrangement is shown in fig. 3, which is intended for inside blinds.

The slats, in this case, are perpendicular. They are

constructed, however, in all respects like the slats shown in fig. 1, excepting that instead of a rod, links, *k*, are used. The cam, also, is provided with a square projection, and the socket is in the key.

These differences, however, are not material, and do not affect at all the operation of the slats.

Having thus fully described my invention,

What I claim, and desire to secure by Letters Patent of the United States, is—

1. The slats *A'*, provided with clamps *a a'*, as and for the purpose described.

2. The slats *A'*, having the clamps *a a'*, in combination with rod *B*, bar *c*, and cam *d*, the whole being con-

structed and operated in the manner described, for the purpose set forth.

3. The cam *e* and bar *e'*, with or without the intermediate connections *e¹ e²*, when arranged as described, in connection, either with the rod of a blind of the usual construction, or a rod attached to the slats by the clamps *h*, as set forth.

This specification signed and witnessed, this 21st day of September, 1868.

S. M. SHERMAN.
